UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LOOM SHUTTLE.

Application filed December 19, 1924. Serial No. 756,898.

To all whom it may concern:

Be it known that I, HARRY A. DAVIS, a citizen of the United States, and resident of Hopedale, in the county of Worcester and State of Massachusetts, have invented an Improvement in Loom Shuttles, of which the following description, in connection with the accompanying drawings, is a specification, like characters on the drawings representing like parts.

This invention relates to loom shuttles, and more particularly to the thread delivery control uncoiling engagement type, wherein a tension member engages the yarn on the thread package within the shuttle chamber.

The filling or weft thread used in loom shuttles is usually wound upon a filling carrier or bobbin in conical layers and during the weaving operation is rapidly drawn from the shuttle as it is picked from one shuttle box to the other, and the present invention provides a tension member for controlling the delivery of thread from the shuttles.

When the shuttle is suddenly arrested in the shuttle box at the end of its flight the filling or weft thread is liable to overrun and in consequence the filling may become snarled or kinked at times, causing breakage or, in case of automatically threading shuttles employed in filling replenishing looms, such condition of the filling may cause the shuttle to be unthreaded. An important feature of the present invention, therefore, consists of a shuttle tension which bears directly upon the mass of filling in the shuttle and conforms to the rounded surface of the mass of filling as such mass gradually becomes depleted. This characteristic of the invention, while rendering the tension member effective in preventing overrunning of the filling in any type of shuttle, renders it particularly advantageous in a shuttle where the filling is to be replenished from time to time by the automatic insertion and ejection of filling carriers or bobbins, because, while acting upon the body of the filling in the shuttle, it does not, in accordance with the present invention, interfere with the automatic ejection of a filling carrier.

Shuttles of the automatically replenishing type usually have an enlarged head or

end portion, to engage holding means in the shuttle, and yet permit the filling carrier or bobbin to be ejected. It is, therefore, important, that the tension member which bears upon the body of the thread or yarn in the shuttle shall not impede the passage of the filling carrier thru the opening in the wall of the shuttle when the filling is replenished.

Another important feature of the invention, therefore, consists of a tension member which extends diagonally across the bobbin chamber in contact with the mass of yarn therein, and is so constructed and arranged and connected to the shuttle itself that it will not interfere with the incoming fresh supply of filling or the outgoing bobbin.

The invention and novel features and combination of parts will best be made clear from the following description and accompanying drawings showing a good, practical form thereof.

Fig. 1 is an under side perspective view of a shuttle embodying the present invention, one of the walls of the shuttle being broken away.

Fig. 2 is a section on the line 2—2 of Fig. 1.

Fig. 3 is a sectional detail showing the yielding arm extending transversely of the bobbin chamber for yieldingly supporting one end of the tension member.

Fig. 4 is an enlarged detail, showing one form of means for securing one end of the tension member to the shuttle.

Fig. 5 is a broken-away perspective of one end of the shuttle, showing a modified form of the invention.

Fig. 6 is a similar view, showing a still further modification.

The invention is herein shown as associated with a filling replenishing shuttle, which as usual has an opening for the passage of an ejected filling carrier or bobbin, but the advantages of the invention may also be utilized in connection with other forms of shuttles.

The shuttle 1 as shown is of the usual automatically replenishing type having a bobbin chamber 2 for the reception of the filling carrier or bobbin 3. At one end of the bobbin chamber the shuttle is provided with the bobbin holding jaws 4 which may be of usual or any preferred construction,

- adapted to engage the rings 5 which are carried by the head 6 of the filling carrier or bobbin, the construction being such that the filling carrier or bobbin in the shuttle 5 may be forced from the shuttle by an incoming filling carrier or bobbin, the ejected filling carrier or bobbin at such times passing, in the present instance, downwardly thru an opening 7, as indicated in Fig. 2. 10 During weaving the filling or yarn in the shuttle is withdrawn therefrom as the shuttle is picked alternately from one side of the loom to the other, and, as indicated in Fig. 5, the shuttle is provided with an 15 automatically threading block designated generally as 8. The threading block 8 may be of any desired construction, and the yarn drawn from the filling carrier or bobbin passes from the thread passage in the 20 threading block outwardly thru the side delivery eye 9 as usual.
- In order that the filling or yarn in the shuttle shall not balloon, or overthrow, or become snarled or kinked during the weaving 25 operation, it is desirable that a too free delivery of the filling from the filling carrier or bobbin may be prevented, especially when the shuttle comes to rest in the shuttle box after its flight across the lay. To this end 30 the present invention contemplates a tension member which extends longitudinally of the shuttle and in a diagonal direction relative to the bobbin chamber to engage the body of the filling or yarn upon the filling carrier or bobbin and control its delivery therefrom. 35 Such diagonal arrangement of the tension member would ordinarily interfere with the ejection of the filling carrier or bobbin in a filling replenishing shuttle, but, in accordance 40 with the present invention, the tension member is connected to the shuttle in such manner that it may yield to permit the passage of the ejected filling carrier or bobbin and return to its initial position to bear upon 45 the mass of filling or yarn of the fresh filling carrier or bobbin.
- The tension member 10 is formed of flexible material such as a spring, elastic webbing, cord, or like filaments so that as the filling 50 is progressively withdrawn from the filling carrier or bobbin it will conform to the contour of the remaining filling. The tension member 10 is secured to the shuttle adjacent one end of the bobbin chamber and 55 extends in a longitudinal and diagonal direction with reference to the bobbin chamber crossing the longitudinal axis thereof, and is supported at its other end by a yielding arm which extends from one side of the 60 bobbin chamber transversely thereof with capacity for yielding movement to permit passage of the ejected carrier or bobbin, as indicated by dotted lines in Fig. 2.
- In the present instance of the invention 65 the tension member 10 is shown in Fig. 4 as connected to an adjusting screw 11 which may be conveniently passed thru the wall 12 of the shuttle and be threaded into a sleeve 13. The adjusting screw 11 is shown as provided with an eye or hook 14, to which 70 one end of the tension member 10 may be secured. This means for securing one end of the tension member to the shuttle has been found a good, practical form of such means, but it is to be understood that the invention 75 is not limited thereto, but that the end of the tension member may be secured to the shuttle by any appropriate or desired securing means.
- Mounted upon the shuttle is a bearing or 80 block 15, and in the present instance such block is preferably secured to the wall 12 of the shuttle in a recess 16 formed therein at the lower portion thereof or adjacent the opening 7. The block 15 has a portion 17, 85 (Fig. 3) extending longitudinally of the shuttle to form a support or bearing for an arm 18. The arm 18 has a longitudinally extending portion 19 adapted to rock in the bearing portions 20 and 21 of the block and 90 between the bearing portions 20 and 21 (Fig. 3) is a spring 22 one end of which is secured to the block as at 23 and the other end of which is secured to the arm 18 as at 24, the tendency of said spring being in an 95 upward direction viewing Fig. 2, to maintain the arm 18 extending transversely of the bobbin chamber. It may be desirable in some instances to provide a stop for limiting the upward movement of the arm 18 under 100 the impulse of the spring 22, and such stop may be variously formed. As indicated in Fig. 3 it may consist of the end portion 25 connected to the arm which may abut against a pin or projection 26 extending from the 105 block 15. Such stop, however, may not always be necessary.
- The free end portion 27 of the arm 18 which extends transversely of the bobbin chamber is preferably located at the side of 110 the bobbin chamber opposite to the securing means 11, as indicated in Figs. 1 and 2, and to such free end portion 27 of the arm 18 the other end of the tension member 10 is secured, the result being that the tension 115 member extends in a diagonal direction across the bobbin chamber to bear upon the body of the yarn on the filling carrier or bobbin. Thus, in the construction shown, both ends of the tension member 10 are supported from the same side wall of the bobbin chamber, and, while this constitutes a preferred form of the invention, in order to secure the maximum amount of yarn control 120 as it is withdrawn from the bobbin or filling carrier in the shuttle, the fixed end of the tension member may be secured at other points than that described so long as the tension member shall extend longitudinally 125 and diagonally of the bobbin chamber to 130

bear upon the mass of yarn on the filling carrier or bobbin and control its delivery therefrom.

From the construction described it will be noted that when filling replenishment is effected, as indicated in Fig. 2, the outgoing filling carrier or bobbin passes downwardly or outwardly from the opening 7 in the shuttle and the tension member 10 swings laterally to one side of the path of the filling carrier or bobbin to permit this passage, as indicated in dotted lines in Fig. 2 and after the passage of the ejected filling carrier or bobbin the yielding arm 18 returns to its initial position to cause the tension member to again function on the mass of yarn last introduced into the shuttle.

In the construction of the invention as shown in Figs. 1 and 2, the yielding arm 18 is placed adjacent the head of the bobbin and this has been found to be a good practical form of the invention. In some cases, however, it may be desirable to support the yielding arm adjacent the opposite end of the shuttle, as indicated in Fig. 5, and to secure the standing end of the tension member 10 to the wall of the bobbin chamber near or adjacent to the head of the bobbin.

This last described disposition of parts is indicated in Fig. 5, wherein the tension member 10 is secured to an arm 28 mounted for yielding movement at the delivery end of the bobbin chamber. In the construction shown by Fig. 5 the yielding arm 28 is formed as a spring having its base portion secured at 29 adjacent the threading block 8. If desired to increase the resiliency or yieldability of the spring arm 28 it may be additionally supplied with a spring similar to the spring 22 hereinbefore described, but this will not always be necessary. In either event, however, the end of the flexible member 10 adjacent the threading block, or at the forward portion of the bobbin chamber, is secured to the yielding arm 28, as indicated in Fig. 5, so that on ejection of a filling carrier the arm 28 may yield to permit ready passage of the tip portion of the filling carrier or bobbin and then return to its initial position.

As indicated in Fig. 5 the base portion of the spring arm 28 is secured at 29 to a plate or projection 30 which may be conveniently secured in the wood of the shuttle at 31.

Instead of making the arm 18 as hereinbefore described with reference to Figs. 1 and 2, such yielding arms may be formed as indicated at Fig. 6, that is it may be made of spring metal and attached to one of the walls of the bobbin chamber. As shown in Fig. 6 the spring arm 32 to the end of which one end of the flexible member is secured is given a half turn in the portion which extends transversely of the bobbin chamber, and the spring arm is shown as

secured to the wall of the bobbin chamber by a plate 33 preferably formed integral therewith. As a convenient means for supporting the plate 33 and yielding arm 32 the wall of the bobbin chamber may be provided with a longitudinally extending metal strip 34 to which the plate 33 may be secured by rivets 35, or other means.

In accordance with one form of the present invention the tension member has at least one end secured to a yielding arm which extends transversely of the bobbin chamber with capacity for yielding movement to permit the ejection of a bobbin or filling carrier from the shuttle, notwithstanding the fact that the tension member itself extends transversely across the path of movement of the filling carrier or bobbin as it is ejected, and the yielding supporting arm may be variously contrived either as indicated in Figs. 1 and 2, or as indicated in Figs. 5 and 6, where the yielding arm is at one end of the bobbin chamber or at the other.

The yielding arm for supporting one end of the tension member for displacement by the outgoing bobbin or filling carrier, is shown as preferably curved to carry the supported end of the tension member up above the lower surface of the mass of yarn, that the tension member may more effectively bear upon an extended surface of the yarn and control delivery thereof. As shown also the yielding arm extends transversely of the bobbin chamber below the filling carrier or bobbin in the shuttle, and it, together with the flexible tension member, moves or swings downwardly on filling replenishment under the impulse of the outgoing filling carrier or bobbin and then returns to initial position with the tension member moved automatically into controlling contact with the new supply of filling.

Claims:

1. A loom shuttle provided with a tension member, extending diagonally across the bobbin chamber to bear upon the yarn therein and a yieldable supporting arm for the tension member extending across the bobbin chamber to be displaced by a bobbin as it is ejected from the shuttle.

2. A loom shuttle provided with a tension member having a flexible body portion extending diagonally across the bobbin chamber to bear upon the yarn package and a yieldable supporting arm for the tension member extending across the bobbin chamber to be displaced by a bobbin as it is ejected from the shuttle.

3. A loom shuttle provided with a tension member extending longitudinally of the bobbin chamber and a yieldable supporting arm for the tension member extending across the bobbin chamber and holding the tension member in diagonal relation thereto

to be displaced by a bobbin as it is ejected from the shuttle.

4. A loom shuttle provided with a tension member crossing the longitudinal axis of the bobbin chamber to bear upon the yarn package, means for securing one end of the tension member to the shuttle at one side of the bobbin chamber, and yielding means secured to the same side of and crossing the bobbin chamber and supporting the flexible member at the opposite side of the bobbin chamber for displacement by a bobbin as it is ejected from the shuttle.

5. A loom shuttle provided with a flexible tension member extending across the longitudinal axis of the bobbin chamber and having one end secured to the shuttle adjacent one end of the bobbin chamber, and a yielding arm extending across the bobbin chamber below the bobbin for supporting the tension member diagonally of the bobbin to yield to the passage of a bobbin as it is ejected from the shuttle.

6. A loom shuttle having a tension member to bear upon the yarn package, one end of the tension member being secured at one end of the bobbin chamber, and a yielding arm extending across the bobbin chamber for supporting the other end of the tension member.

7. A loom shuttle having a flexible tension member extending diagonally of the bobbin chamber to bear upon the yarn package, and a yielding arm extending transversely of the bobbin chamber and supporting one end of the tension member for displacement by an outgoing bobbin.

8. A filling replenishing loom shuttle having an opening for the discharge of a filling carrier or bobbin, a flexible tension member diagonally arranged in the bobbin chamber to bear upon the yarn on the carrier or bobbin, and a support for one end of the flexible member constituted as a yielding arm extending transversely of the bobbin chamber constructed and arranged to yield for the passage of an ejected filling carrier or bobbin.

9. A filling replenishing loom shuttle having a yielding arm mounted at one side of the bobbin chamber and extending transversely thereof, and a flexible tension mem-

ber disposed diagonally of the shuttle and having one end secured to the yielding arm at one side of the bobbin chamber and its other end secured to the shuttle adjacent the other end of the bobbin chamber.

10. A filling replenishing loom shuttle having a diagonally extending tension member to bear upon the yarn mass in the shuttle, and yielding means extending across the bobbin chamber for supporting one end of the diagonally extending tension member that the latter may be carried out of the path of the bobbin as it is ejected from the shuttle.

11. A filling replenishing loom shuttle having a diagonally extending tension member to bear upon the yarn mass in the shuttle, a spring arm connected to the shuttle at one side of the bobbin chamber and extending transversely thereof and yielding to the passage of an ejected filling carrier or bobbin, and a diagonally supported tension member to bear upon the body of the yarn having one end secured to said spring arm for movement therewith out of the path of a passing filling carrier or bobbin.

12. A shuttle having a bobbin chamber for a yarn package, a curved yielding arm connected to the shuttle and extending transversely of the bobbin chamber near one end thereof, a flexible tension member having one end secured to the flexible arm and its other end connected to the shuttle near the opposite end of the bobbin chamber with the intermediate portion of the flexible tension member bearing upon the mass of yarn in the bobbin chamber.

13. A filling replenishing shuttle having a bottom opening for the passage of a bobbin or filling carrier, a yielding arm extending transversely of the bobbin chamber below the bobbin or filling carrier, and a flexible tension member having one end secured to the yielding arm and its other end connected to the shuttle to cause the intermediate portion of the tension member to bear upon the mass of yarn in the shuttle and yield with the arm to the passage of a filling carrier or bobbin.

In testimony whereof, I have signed my name to this specification.

HARRY A. DAVIS.
